STRAIGHTEDGE

Filed Aug. 13, 1925

FIG. 2.

Inventor:

J. W. Heltzel,
Thomas Miller

Attorney.

UNITED STATES PATENT OFFICE

JOSEPH WILLIAM HELTZEL, OF WARREN, OHIO

STRAIGHTEDGE

Application filed August 13, 1925. Serial No. 49,998.

The present invention relates to straight-edges, and aims to provide a novel and improved device of that kind intended especially for use in connection with the building of 5 concrete roads, sidewalks, and the like.

Heretofore, it has been the practice to use straight-edges made of wood. Such straight-edges have not only been cumbersome to handle, but, furthermore, the wood 10 would warp thus rendering the straight-edges untrue. The bottom surfaces or lower edges of wooden straight edges becoming wet by contact with damp concrete, while the top surfaces of the straight edges are 15 exposed to the sun, results in the wood drying out at the top, while remaining moist at the bottom. This results in the wood warping and getting out of shape so that the straight-edge is no longer accurate. Diffi- 20 culty has also been experienced owing to the breakage of the straight-edges and the handles therefor, such handles being long and also composed of wood.

It is an object of the invention to provide 25 a straight-edge for use in concrete and similar work which is composed of metal, so as to be durable and non-warping, and the construction being such that the device is not only practical and efficient in use, but is also 30 light in weight, and capable of being conveniently disassembled for purpose of compact storage or shipment.

With the foregoing and other objects in view, which will be apparent as the description 35 proceeds, the invention resides in the construction and arrangement of parts, as hereinafter described and claimed, it being understood that changes can be made within the scope of what is claimed, without departing 40 from the spirit of the invention.

The invention is illustrated in the accompanying drawing, wherein—

Figure 1 is a perspective view of the improved straight-edge as in use.

Fig. 2 is an enlarged end view of the straight edge, portion of the handle being broken away.

The straight-edge proper, indicated at 7, is composed of metal and is hollow, the same 50 being a metal tube of rectangular cross-sec-

tion with its narrower sides at the top and bottom. A metal handle 8 is provided, which is also hollow, the same being a metal tube of circular cross-section, and the lower end of the handle is connected to the intermediate 55 portion of the straight edge 7 at one of the broader sides of said straight edge. It is preferable that the straight-edge 7 be ten feet in length, while the handle 8 is twelve feet in length, and they are both of twenty-two 60 gage metal. The straight edge 7 is one-half inch in width and is one and one-half inches deep, while the handle has an external diameter of one and one-quarter inches. However, the dimensions may vary. A device of 65 the dimensions indicated weighs eight and one-half pounds, so that it can be readily manipulated, being comparatively light in weight. Furthermore, with ordinary usage the straight edge and handle are not apt to 70 break, it being apparent that there is considerable leverage on the handle 8 when lifting the straight edge by the upper terminal portion of the handle as shown in Fig. 1. The 75 handle and straight edge are detachably connected. Thus, the lower terminal of the handle 8 is welded, brazed or otherwise secured to a plate 9 in abutment with said plate, and said plate bears against the rear side of the straight edge 7 and is secured to said straight 80 edge by bolts 10 or other securing elements at opposite sides of the handle extending through apertures in the plate 9 and straight edge 7. The plate 9 preferably projects above the straight edge 7 so as to contain a 85 name-plate or label 11. The upwardly projecting portion of the plate 9 not only serves as a convenient means for the conspicuous provision of a name-plate or label, but also facilitates using the straight edge with the 90 same edge lowermost at all times, thereby eliminating the inversion of the device. When shipping or storing the device, by removing the bolts 10, the handle and straight edge are readily separated, and may be placed 95 together in close parallel relation, for compact storage or shipment.

The device is intended especially for use in the building of concrete roads, sidewalks, and the like, as suggested in Fig. 1. The 100

handle 8 is held in the hands for applying the straight edge 7 to the surface of the concrete 12 between the side forms or rails 13. The surface of the concrete may be tested to determine whether there are high or low spots in the concrete, so that same may be remedied before the concrete has hardened. The device being of T-shape, with the handle at right angles with the straight edge, enables the straight edge to be placed longitudinally of the road or sidewalk with the handle projecting to one side, so that the device may readily be manipulated by a workman at one side of the road or sidewalk. The device being constructed entirely of metal will be durable, and will not be affected by moisture. The straight edge 7 being of angular cross-section will remain straight.

Having thus described the invention, what is claimed as new is:—

- 20 1. A straight edge for use in the building of concrete surfacing structures comprising a tubular metal member of angular cross-section adapted to be placed on the surface of plastic concrete, and a handle having one end connected to said member between the ends of and at right angles with said member, for manipulating said member over the surface of the concrete.
- 25 2. A straight edge for use in the building of concrete surfacing structures comprising a tubular metal member of angular cross-section adapted to be placed on the surface of plastic concrete, and a tubular metal handle of circular cross-section having one end connected to said member between the ends of and at right angles with said member, for manipulating said member over the surface of the concrete.
- 30 3. In testimony whereof I hereunto affix my signature.

JOSEPH WILLIAM HELTZEL.
